SUPPORT AND RELEASE MEANS FOR BOBBIN RECEIVERS

Gabriel C. Beatrice, Shrewsbury, Mass., assignor to Crompton & Knowles Loom Works, Worcester, Mass., a corporation of Massachusetts

Application December 22, 1945, Serial No. 636,948

7 Claims. (Cl. 139—255)

1

This invention relates to weft replenishing looms and it is the general object of the invention to provide a spent bobbin receiver removable from its normal position by a downward motion.

Weft replenishing looms discharge depleted or spent bobbins downwardly along a bobbin chute which traverses a given back and forth path as the lay reciprocates. The bobbin receiving mouth of the bobbin receiver ordinarily extends under the forward part of this path so that discharged bobbins can enter the receiver. The usual bobbin can which rests on the floor must first be pulled forwardly and then lifted to empty the bobbins in it. The can is free to be raised without first being moved forwardly, and if this should happen the bobbin chute might strike the can. It is an important object of my present invention to mount a bobbin receiver in such manner that it must be moved downwardly away from the path of the chute before it can be manipulated for bobbin emptying purposes.

It is another object of my invention to provide a support and receiver unit so formed that upward movement of the unit will establish holding relation with the support by a means, such as a spring lock, which will permit downward bodily detachment of the unit from the support by a downward force directed downwardly on the unit.

With these and other objects in view as the description proceeds, my invention resides in the combination and arrangement of parts herein-after described and set forth.

In the accompanying drawings, wherein a convenient embodiment of my invention is set forth,

Fig. 1 is a side elevation of the front part of a loom having my present invention applied thereto,

Fig. 2 is a front elevation looking in the direction of arrow 2, Fig. 1,

Fig. 3 is an enlarged front elevation in the direction of arrow 3, Fig. 1,

Fig. 4 is a side elevation looking in the direction of arrow 4, Fig. 3,

Fig. 5 is a horizontal section on line 5—5, Fig. 4, and

Fig. 6 is a diagrammatic view similar to Fig. 4 indicating the bobbin receiver unit bodily disconnected from its support.

Referring to Figs. 1 and 2, the loom frame 10 supports a backwardly and forwardly reciprocating lay 11 provided with a shuttle box 12 for a shuttle S. A bobbin chute 13 secured to the lay extends downwardly and forwardly from the shuttle box and guides the spent or depleted bobbins as they are discharged from the shuttle during weft replenishing operations of the loom.

2

The bobbin chute swings along a back and forth path and bobbins are discharged when the lay is on front center position, or to the left as viewed in Fig. 1.

5 The spent bobbins are collected in a receiver designated generally at R and including a cloth bag B and a frame F to which it is attached. The bag has a mouth 20 which extends rearwardly of and under the front part of the path of the chute so that the discharged bobbins can enter the bag.

A support or supporting unit 21 is secured at 22 to the lower part of the loom frame 10 and has its forward end as viewed from the front of the loom formed with a head 23 shown in Figs. 3 and 15 4. As shown in Fig. 5a vertically extending slot 24 has its inner side nearest the loom formed by a wall 25 of head 23 and has its outer side partly closed by front and back flanges 26 and 27, respectively, having reference to the front of the loom.

20 These flanges are spaced from wall 25 and form with the latter front and back pockets 28 and 29 respectively. Flanges 26 and 27, and pockets 28 and 29 are inclined downwardly and away from each other, as shown in Fig. 4, so that slot 24 is 25 wedge shaped and tapers upwardly.

Front wall 30 of head 23 is provided with a spring plunger 31 made substantially as shown in Fig. 4. The plunger has a rounded nose 32 projecting into front pocket 28 and is hollow to receive a spring 33 between the nose and a plate 34 secured as at 35 to front wall 30. A flange 36 is received by a recess 37 in wall 30 and limits rearward movement of the plunger by the spring. Wall 30 has a bore 38 in which the plunger slides,

30 and plate 34 is recessed at 39 to receive flange 36 when the latter moves forwardly, or to the left, from the normal position shown in Fig. 4. The frame F of the bobbin receiver has inner and outer side members 45 and 46, respectively, 35 joined at their lower ends by a cross bar 47. The upper ends of the side members are bent rearwardly and preferably downwardly to form arms 48 from which the bag is suspended. A top cross bar 49 joining the side members reinforces them 45 and provides a hand hold. Cords or the like 50 connect the front part of the bag to the side members and limit rearward movement of the bag.

In order that the frame F may be mounted on support 21 I provide a foot 55 having a curved 50 groove 56 therein to receive parts of side member 45 and bottom cross bar 47. These latter parts are secured as by welding to the foot, and the latter, together with frame F and bag B, forms the bobbin receiver unit R.

Foot 55 has front and back ribs 60 and 61,

55

respectively, inclined as shown in Fig. 4 to fit the pockets 28 and 29. Front rib 60 has a depression or notch 62 to receive the spring plunger. This notch is so located that the plunger will not enter it until the ribs are snugly seated in the pockets.

Under normal conditions the parts are in the position shown in Figs. 1, 2 and 4, the spring plunger holding the unit R in normal raised position with foot 55 fitting closely into the slot 24 and with the bobbin receiver mouth of bag B projecting under the front part of the path traversed by the bobbin chute. As successive weft replenishing operations occur the spent bobbins accumulate in the bag and in time require emptying.

The attendant will then push downwardly on the frame F with sufficient force to push notch 62 below the spring plunger, thus releasing the foot 55. The receiver is then lowered away from the path of the bobbin chute until the foot is out of slot 24, after which the receiver R can be moved outwardly so that foot 55 will clear head 23, after which the bag can be inverted to empty the bobbins in it. The bottom and top cross bars of frame F may be grasped by the attendant to perform this operation.

To return the receiver unit to normal position foot 55 will be located with its ribs under the pockets and then lifted until plunger 31 is again in notch 62, after which the foot will be snugly fitted into slot 24 and the unit R will again be in normal position.

In order to facilitate entry of the foot 55 into slot 24 the head 23 is preferably provided with a guide fin 70 depending from the rear flange 27 and extending outwardly from it, see Figs. 4 and 5. Also, a guide apron 71 aligned with wall surface 25 may hang down from head 23 and extend upwardly and forwardly from guide 70 to wall 30.

From the foregoing it will be seen that I have provided a mounting for the bobbin receiver unit R so constructed that the latter must be moved downwardly from the path traversed by the chute before it can be detached from the support 21. The wedge shape of the foot 55 and the slot which it fits prevents the receiver unit from being disconnected from the support by an upward motion. The spring plunger is strong enough to support the receiver unit when it is full of bobbins, but can be readily overcome by a force directed downwardly on unit R.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom from which depleted bobbins are discharged, a support having a downwardly opening slot therein, a bobbin receiver unit having a foot formed to enter said slot by upward motion thereinto, and means normally operative to hold said foot in said slot to hold said unit in normal position and responsive to a downward force to effect disengagement of said foot downwardly from said support.

2. In a weft replenishing loom from which bobbins are discharged downwardly along a chute which traverses a given back and forth path, a support fixed with respect to the loom and hav-

ing a downwardly opening slot therein, a bobbin receiver unit having a mouth extending under said path when said unit is in normal position, a foot on said unit formed to enter said slot by upward motion thereinto, and means normally holding said foot in said slot to maintain the unit in normal position, said means being responsive to a downward force to disconnect said foot from said support and permit motion of said unit downwardly from said path.

3. In a weft replenishing loom from which bobbins are discharged downwardly along a chute which traverses a given back and forth path, a supporting unit mounted on the loom, a bobbin receiver unit having a bobbin receiving mouth, and connections between said units holding said receiver unit with said mouth extending under part of said path, said units being so constructed as to prevent separation thereof by upward motion of the receiver unit, but permit separation thereof by downward motion of the receiver unit.

4. In a weft replenishing loom from which bobbins are discharged downwardly along a chute which traverses a given back and forth path, a bobbin receiver unit having a bobbin receiving mouth, and support means for said unit constructed to hold said unit normally with the mouth thereof extending under part of said path, said support means and unit having cooperative parts which permit downward motion of the receiver unit but prevent upward motion thereof relatively to the support means.

5. In a weft replenishing loom from which depleted bobbins are discharged, a receiver unit for the discharged bobbins, a foot member forming part of said unit, a support member for said foot member, said members having complementary parts caused to fit together by upward movement of the foot member relatively to the support member, and yielding means on one of said members normally cooperating with the other member to hold said members together with said receiver unit in normal position, said means being yieldable to a downwardly directed force to disconnect said members.

6. In a weft replenishing loom from which depleted bobbins are discharged, a receiver unit for the discharged bobbins, a foot member forming part of said unit, a support member for said foot member, said members having complementary parts caused to fit together by upward movement of the foot member relatively to the support member, and a spring plunger on one of said members normally cooperating with the other member to hold said members together with said receiver unit in bobbin receiving position, said spring plunger being yieldable to a downwardly directed force to effect disconnection of said members.

7. In a weft replenishing loom from which depleted bobbins are discharged, a receiver unit for the discharged bobbins having an upwardly tapering foot, a support having an upwardly tapering opening therein receiving said foot, and resilient means normally holding said foot in said opening with said unit in bobbin receiving position and yieldable to a downward force exerted through said foot to effect bodily separation of said foot and unit downwardly from said support.

GABRIEL C. BEATRICE.
